CLAIM

The ornamental design for a tailpipe, as shown and described.

DESCRIPTION

1. Tailpipe

1.1 is a top, rear, and left side perspective view of a tailpipe embodying our new design;

1.2 is a right side elevation view thereof;

1.3 is a left side elevation view thereof;

1.4 is a top, rear, and right side perspective view thereof;

1.5 is a top plan view thereof;

1.6 is a rear elevation view thereof;

1.7 is a top, front, and right side perspective view thereof;

1.8 is a bottom plan view thereof; and

1.9 is a front elevation view thereof.

The “automobili Lamborghini” and design mark, appearing at least in part in Figures 1.1, 1.3, 1.4, 1.5, and 1.6 is a trademark of Automobili Lamborghini S.p.A. The “AKRAPOVIČ” and design mark, appearing at least in part in Figures 1.1, 1.2, 1.3, 1.4, 1.5, 1.6, and 1.7 is a trademark of Igor Akrapovič. The “automobili Lamborghini” and “AKRAPOVIČ” trademarks, shown on the collar around the
